UNITED STATES PATENT OFFICE.

JOSEPH A. WARREN, OF MANCHESTER, NEW HAMPSHIRE.

TANK-CLOSURE.

1,366,854.

Specification of Letters Patent. Patented Jan. 25, 1921.

Application filed September 30, 1920. Serial No. 413,685.

To all whom it may concern:

Be it known that I, JOSEPH A. WARREN, a citizen of the United States, residing at Manchester, in the county of Hillsborough, 5 and State of New Hampshire, have invented certain new and useful Improvements in Tank-Closures; and I do declare the following to be a full, clear, and exact description of the invention, such as will enable others skilled in the art to which it appertains to make and use the same.

This invention relates broadly to improvements in closures, and it has more particular reference to an improved closure especially, 15 although not necessarily, designed for use in connection with automobile gasoline storage tanks.

One object of the invention is to provide a self-closing valve for tanks or other containers in which volatile liquids such as gasoline are stored, the valve being automatically seated by spring pressure, and when opened and released, immediately returnable to its normal closed position to effect an extremely tight closure; the construction and arrangement of the closure being such as to permit it to yield and permit the escape of excessive gas from the tank, thus serving as a safety valve.

Another object of the invention is to provide a closure which is composed of comparatively few simple and inexpensive parts which are so correlated that they insure effective results and permit easy and ready 35 unseating of the valve when the tank is being filled.

Other objects and advantages of the invention will be apparent during the course of the following description.

In the accompanying drawings forming a part of this specification and in which like numerals are employed to designate like parts throughout the same:

Figure 1 is an elevational view of a device 45 constructed in accordance with my invention, the same being shown in the manner in which it is associated with the filling opening in a gasoline tank.

Fig. 2 is a sectional view thereof which 50 more clearly discloses the construction and arrangement.

Fig. 3 is a view similar to Fig. 2 showing the valve in open position to permit the tank to be filled.

Figs. 4 and 5 are sections taken on the lines 4—4 and 5—5 respectively of Fig. 2.

By referring to the drawings, it will be seen that the numeral 1 designates a tank provided with a filling opening 2 which under ordinary circumstances is closed by 60 means of a screw-cap. It is my intention to do away with this screw-cap and substitute my novel automatically spring-closed valve device. This device comprises a closure 3 including a channel portion 4 to accommodate the insertion of a yieldable packing-ring 4^a which engages the tank in the manner disclosed to insure a tight closing. In addition to this channel portion, this valve also includes a depending part 5 which extends through the opening 2 and into the interior of the tank. Suitable air vents 6 will, of course, be provided. Disposed in the tank adjacent the opening 2 is a substantially rectangular plate 7 which is provided 70 with a central opening registering with the opening 2, the portion of the plate surrounding this opening being bent inwardly to provide an endless flange 8 which serves a purpose to be hereinafter described. This 75 plate is provided with combined anchoring and anti-slipping means being preferably in the form of spurs 9 which are formed by simply bending the corners of the plate laterally to bring them into engagement with 80 the tank. It is to be noted that the plate referred to is of such a width that it may be turned endwise and the device easily inserted through the hole in the tank.

As before indicated, the valve 3 is self-closing and it is here shown as being closed by means of a coiled spring 10 which surrounds the flange 8 at one of its ends and bears against the plate 7, it being connected with the valve through the medium of flexible connectors in the form of chains 11 which are connected at their inner ends to a channel member 12 in which the inner end of said coiled spring is seated. With this construction and arrangement, it is obvious 90 that the valve 3 may be grasped and pulled outwardly against the action of the coiled spring and caused to assume a position approximating that shown in Fig. 3, whereby 95 the funnel or spout of the gasoline can may 100 be inserted through the filling opening 2 in order to place the necessary supply of fuel in the tank. As soon as the valve is released, it will be automatically returned to its normal position by means of the spring and 105 parts which coact therewith.

From the foregoing description, it will

be seen that the coiled spring not only serves to automatically return the valve to closed position, but it exerts considerable pressure on the valve and insures a fluid-tight connection between the latter and the tank. This is further insured by the employment of the yieldable packing ring. The coiled spring is properly retained in place by the novel abutment or plate which is in turn retained in its position by means of the spurs which dig into the tank. The parts employed in the make-up of my improved closure device are so simple that the cost of manufacture of the device is comparatively small.

These and other advantages and features of my invention, have no doubt, become apparent from the foregoing description.

A careful consideration of the foregoing description taken in connection with the accompanying drawings, is thought to be sufficient to enable persons skilled in the art to which this invention relates, to obtain a clear understanding of the same and the manner in which it operates. For this reason, a more lengthy description is deemed unnecessary.

Since probably the best results may be obtained with the construction and arrangement herein disclosed and described, this construction and arrangement is taken as the preferred embodiment of my invention. However, I wish it to be understood that minor changes in the shape, size, and arrangement of parts may be resorted to with-

out departing from the spirit of the invention or the scope of the subjoined claim.

I claim:

In combination, a container provided with a filling opening, a substantially conical valve closing and extending through said opening, a coiled spring for closing and retaining the valve closed, a channel-shaped ring in the container receiving the inner end of said spring, said ring carrying opposed hooks, chains connected to the valve and said hooks, and a substantially square flat plate of a size to permit it to be inserted through the aforesaid filling opening, said plate constituting an abutment for the spring and being disposed within the container and arranged between the upper end of the spring and the valve, being centrally apertured to permit free passage of the fluid therethrough and also permitting passage of the pointed end of the valve therethrough, said opening being surrounded by a laterally downturned flange extending into the upper end of the spring to prevent lateral displacement of the latter, the corners of the plate being bent laterally up to provide spurs which engage the adjacent wall of the container for retaining the plate in position, said spring serving the additional function of insuring an effective engagement of the spurs with the container wall.

In testimony whereof I have hereunto set my hand.

JOSEPH A. WARREN
